US00D922045S

(12) **United States Design Patent** (10) **Patent No.:** **US D922,045 S**
Goussev et al. (45) **Date of Patent:** **** Jun. 15, 2021**

(54) **SOLE**

(71) Applicant: **adidas AG**, Herzogenaurach (DE)

(72) Inventors: **Stanislas Goussev**, Nuremberg (DE);
Carl Arnese, Portland, OR (US); **Felix Braun**, Nuremberg (DE)

(73) Assignee: **adidas AG**, Herzogenaurach (DE)

(**) Term: **15 Years**

(21) Appl. No.: **29/703,580**

(22) Filed: **Aug. 28, 2019**

Related U.S. Application Data

(63) Continuation of application No. 29/590,094, filed on Jan. 6, 2017, now Pat. No. Des. 862,051.

(57) **CLAIM**

The ornamental design for a sole, as shown and described.

DESCRIPTION

The FIGURE is a bottom view of a sole showing the claimed design.

The broken lines in the FIGURE and the areas within the broken lines show portions of the sole that form no part of the claimed design. The areas within the solid lines in the FIGURE form the claimed design.

1 Claim, 1 Drawing Sheet
